(57) CLAIM

The ornamental design for a barrel cork cage ornament, as shown and described.

DESCRIPTION

FIG. 1 is a perspective view of a barrel cork cage ornament showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top view thereof; and,

FIG. 7 is a bottom view thereof.

The broken line showing of the text and label on the barrel cork cage ornament forms no part of the claimed design.
